ELECTRODE.

1,007,151.

Specification of Letters Patent. Patented Oct. 31, 1911.

Application filed May 17, 1910. Serial No. 561,848.

To all whom it may concern:

Be it known that I, EBEN C. SPEIDEN, a citizen of the United States, residing at Niagara Falls, in the county of Niagara and 5 State of New York, have invented certain new and useful improvements in Electrodes, of which the following is a specification.

This invention relates to electrodes designed 10 particularly for electrothermic work, as for example the production of steel or other metallic products in the electric furnace.

For electrothermic purposes it is often advantageous 15 to use an electrode of such cross-section as to afford a wider distribution of current to the bath than could be had from the same mass disposed in the usual round or rectangular shape. It is further desirable 20 that the electrodes should be so constructed that they may be joined at the ends in such manner that new sections may be added as the electrode is consumed.

The present invention is a construction 25 wherein the above mentioned advantages are secured. The sections of the electrodes are adapted to intermesh with each other, and each section is composed of conductive plates disposed in angular relation to each 30 other, the effect of this construction being the exposure to the bath of a comparatively large electrode area. The sections may be integral masses of conductive material such as carbon or graphite of suitable cross-section, but they are usually composed of separate plates secured together for example by 35 carbon or graphite pins or by other suitable means. The unit cost of manufacture of electrodes increases with the size above a 40 certain limit, and in the larger sizes it is difficult to secure uniformity and homogeneity, these qualities being often sacrificed to size. It is preferred therefore to construct the sections, particularly when these 45 are of comparatively large size, of several plates or parts which are usually of better quality than an integral electrode having the same dimensions as the composite electrode.

The sectional construction in accordance 50 with the present invention presents an important advantage in that it affords a joint of good electrical conductivity and high mechanical strength without the necessity 55 of machining the ends of the sections. The

sections may be constructed of plates or bars of graphite or carbon of standard forms and dimensions, the conformation required for the joint being obtained by assembling these standard plates in certain definite relations to each other.

It is important that the joints between the sections should be of proper conductivity to avoid undue heating, and in this respect electrodes constructed in accordance with 65 the present invention possess decided advantages, for with a given cross-section of carbon or graphite the area of contact at the joints may be made relatively great. The end-to-end joints may be made by 70 simply abutting the pieces, with or without a filling of powdered graphite or graphite cement; or the abutting surfaces of the respective sections may be tapered, threaded or secured by pins as may be desired to 75 further increase the conductivity of the joint. The electrodes may be made from graphitized or nongraphitic carbon, or from other materials if desired.

The electrodes may be hollow or solid in 80 cross-section, and if hollow may be either tubular or prismatic. In the case of hollow electrodes it is preferred to insert within them, at suitable intervals, plugs or filling masses which serve several important purposes. These plugs may in some cases be composed of concrete or other material not objectionable to the operation in view, serving to prevent the escape of gases through 85 the electrode and the consequent overheating of the electrode. Preferably however they are of carbon or graphite and are disposed in proximity to the joints, serving the further purposes of increasing the mechanical strength and the electrical conductivity at these points. The electrode may in some cases be filled with concrete or other material not prejudicial to the operation.

For a full understanding of my invention reference is made to the accompanying 100 drawings wherein several illustrative forms of electrodes embodying the invention are shown, it being understood that the invention is not restricted to the particular constructions chosen for illustration.

In said drawings—Figures 1, 3, 5 are perspective views of certain electrode constructions, whereof two sections of each are illustrated; Figs. 2, 4, 6 are plan views of the constructions of Figs. 1, 3, 5 respectively; 110

and Fig. 7 is a longitudinal section of a cylindrical electrode, showing several types of joint.

The construction illustrated in Figs. 1 5 and 2 is a hollow electrode, square in cross-section and composed of plates 1 of graphitic or non-graphitic carbon, so disposed that the edge of each plate abuts the side of the adjacent plate in regular progression. The 10 plates are secured together by carbon or graphite pins or screws 2, or by other suitable means. In this construction the plates of each section are of equal length and similar shape, and the opposite plates are 15 extended beyond the intermediate plates in such manner as to form an intermeshing joint with a similarly constructed section, as clearly shown in Fig. 1. 3 represents a plug which fills the interior of the prism 20 and serves to strengthen the joint between the sections as well as to prevent the upward movement of gas through the electrode. If the plug is composed of carbon or graphite, as is preferably the case, it likewise 25 greatly increases the conductivity at the joint. As illustrated the plug is secured to one of the sections by a pin 4 and extends upwardly in position to enter the adjacent section.

30 Figs. 2, 3 illustrate an essentially similar construction with the exception that all of the plates 1 terminate in different planes, whereby the abutting joints are staggered and the electrical conductivity of the joints 35 somewhat improved.

Figs. 5, 6 illustrate a construction wherein the plates 1 are disposed substantially radially, opposite plates extending beyond the intermediate plates to form an intermeshing joint as in Fig. 1. The opposite plates may terminate in the same or in different planes as desired.

Fig. 7 shows a hollow cylindrical electrode composed of sections 5, 6, 7, 8, which 45 may be connected together in any suitable manner. For example, the sections may merely abut as indicated at 9, in which case a close fitting carbon or graphite plug 10 is applied to the interior of the cylinder 50 in such manner as to engage both sections, this plug being preferably secured to at least one section by a graphite pin 11. The conductivity of a joint of this character

may be further increased by the provision between abutting surfaces of powdered 55 graphite or graphitic cement. Or a screw joint may be employed as illustrated at 12, with or without a plug or carbon or other material. At 13 in Fig. 7 a taper joint is illustrated in connection with a plug 10. 60

In the use of these constructions it will be understood that the current is conveyed to one or more of the sections by appropriate clamps or equivalent terminals as indicated by way of example at 14 in Fig. 7; 65 and that as the electrode is consumed new sections are added, the position of the terminal being shifted as required.

I claim:

1. An electrode composed of intermeshing 70 sections, each consisting of a plurality of conductive members assembled in lateral contact, said members disposed in angular relation to each other, whereby an added surface of contact with the charge is provided.

2. An electrode section consisting of a plurality of conductive members assembled in lateral contact and terminating in different planes, said members disposed in angular relation to each other, whereby an added 80 surface of contact with the charge is provided.

3. A hollow electrode composed of sections the ends of which are adapted to intermesh.

4. A hollow electrode composed of similar sections the ends of which are adapted to intermesh.

5. A hollow electrode provided with 90 means arranged intermediate its ends for preventing the passage of gases.

6. A hollow electrode composed of intermeshing sections and having an interior filling at the region of joinder of said sections.

7. A hollow electrode composed of intermeshing sections and having an interior conductive filling at the region of joinder of said sections.

In testimony whereof, I affix my signature in presence of two witnesses.

EBEN C. SPEIDEN.
